COMBINATION FURNITURE

Nimrod Franklin Hart, Portsmouth, Va.

Application October 31, 1941, Serial No. 417,398

1 Claim. (Cl. 312—33)

The present invention relates generally to new and useful improvements in furniture, and has for its primary object to provide, in a single device, a unique combination and arrangement of altar, reading table and book cabinet.

Another very important object of the invention is to provide a piece of combination furniture of the aforementioned character comprising a plurality of folding kneeling stools of novel construction.

Other objects of the invention are to provide a piece of combination furniture of the character described which will be comparatively simple in construction, strong, durable, highly efficient and reliable in use, compact, light in weight, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of the device, showing one of the front stools in operative position.

Figure 2 is a view in side elevation thereof.

Figure 3 is a vertical sectional view, taken substantially on the line 3—3 of Figure 2 with one of the side stools in operative position.

Figure 4 is a top plan view showing all of the stools in open or operative position.

Referring now to the drawings in detail, it will be seen that the embodiment of the invention which has been illustrated comprises a cabinet structure of suitable material and dimensions which is designated generally by reference numeral 1. The cabinet 1 includes supporting legs 2 having mounted thereon side and back panels 3 and 4, respectively, a top 5 and a bottom 6. As illustrated to advantage in Figure 3 of the drawings, the back panel 4 extends below the bottom 6 of the cabinet.

The back legs 2 of the cabinet extend above the top 5 thereof, as at 7, and mounted thereon is a rail 8 which may function as a support for a suitable lamp and other devices or articles. A back board 9 is secured on the front of the upper portions 7 of the back legs 2. Pairs of hinged doors 10 on the front of the cabinet 1 provide access thereto.

Mounted on the top 5 of the cabinet 1 is a platform 11 providing a reading table. This platform comprises a forwardly sloping top 12.

The platform 11 is spaced inwardly from the front and sides of the cabinet 1. In this manner arm supporting surfaces or rests 13 are provided in front of and at the sides of the platform 12. These arm rests, also the platform 12, are provided with a suitable covering material, preferably green felt.

Hingedly mounted on the lower portion of the cabinet 1 is a plurality of folding kneeling stools 14. In the embodiment shown, four such stools have been illustrated, two on the front and one on each side of the cabinet 1. As the kneeling stools 14 are similar in construction and operation, a detailed description of one will suffice for all.

Each stool 14 includes an elongated base 15 in the form of a plank of suitable material having one edge pivotally secured at 16 to the lower portion of the cabinet structure 1. Thus, the base 15 is mounted for swinging movement in a vertical plane. A cushion 17 is provided on top of the base 15. Secured beneath the base 15 are longitudinally spaced intermediate and outer plates 18 and 19, respectively. Hingedly mounted at 20 on the inner end portions of the plates 19 are legs 21 in the form of panels. A cleat 22 is secured at an intermediate point on the plate 18 and hingedly mounted on said cleat is a pair of braces 23 which are also in the form of panels. Pulls in the form of loops 24 are mounted for swinging movement on the legs 21. Projecting from the free end portions of the braces 23 are pegs or lugs 25.

The construction and arrangement is such that the stools 14 are adapted to be folded and swung upwardly on their pivots 16 into the lower portion of the cabinet structure 1 beneath the bottom 6 thereof. When the stools are in folded or inoperative position, the legs 21 are folded against the plates 19 and the braces 23 are folded against the plates 18. Of course, when the stools are to be used, they are swung downwardly on their pivots 16. The legs 21 are swung to open position on their hinges 20. When the legs 21 reach a position at right angles to the plates 19 they are arrested or prevented from swinging past this position by the engagement of the hinged end portions thereof with the inner ends of the plates 19. This is shown to advantage in Figure 1 of the drawings. The braces 23 are then open and the loops 24 are engaged over the lugs 25 for detachably securing said braces to the legs 21.

It is believed that the many advantages of a combination device constructed in accordance with the present invention will be readily un-

derstood, and although a preferred embodiment of said device is as illustrated and described, it is to be understood that changes in the details of construction may be resorted to which will fall within the scope of the invention as claimed.

What is claimed is:

An article of furniture comprising a cabinet structure, and a folding stool mounted on the lower portion of said cabinet structure and adapted to swing thereinto, said stool including a base pivotally secured to the cabinet structure for swinging movement in a vertical plane, a cushion on one side of the base, spaced intermediate and outer plates secured on the opposite side of said base, legs hingedly mounted on the inner end 15

portions of the outer plates for supporting the stool in operative position, the hinged end portions of said legs being engageable with the inner ends of said outer plates for positively limiting the swinging movement of said legs toward operative position, a cleat mounted on the intermediate plates, braces hingedly mounted on said cleat, lugs projecting from the braces, and loops on the legs engageable with the lugs for releasably securing said legs in operative position, said legs and braces comprising panels adapted for side abutting engagement with the plates when the stool is in inoperative position.

NIMROD FRANKLIN HART.
